CARD DISPLAYING APPARATUS

Joseph E. Wood, Toronto, Ontario, Canada

Application November 15, 1948, Serial No. 60,110

4 Claims. (Cl. 40—36)

1

This invention relates to a card displaying apparatus, appertaining particularly to an advertising machine in which a series of cards or the like are successively exhibited for a brief period.

Objects of the invention are to provide (1) a card changing apparatus in which a plurality of suspended cards are consecutively removed one at a time from the front of the pack and replaced at the rear; (2) quiet, smooth-running mechanism for so handling the cards and an attractive housing for the card pack and (3) mechanism through which the card on one end of the pack is clearly displayed.

A further object of the invention is to provide such an apparatus that is characterized by structural simplicity, durability and operative efficiency, and that being capable of manufacture, servicing and operation at reasonable cost is thereby rendered commercially desirable.

To the accomplishment of these and related objects as shall become apparent as the description proceeds, the invention resides in the construction, combination and arrangement of parts as shall be hereinafter more fully described, illustrated in the accompanying drawings and pointed out in the claims hereunto appended.

The invention will be best understood and can be more clearly described when reference is had to the drawings forming a part of this disclosure wherein like characters indicate like parts throughout the several views.

In the drawings:

Figure 1 is a sectional rear elevation of this apparatus as taken on line 1—1 of Figure 2;

Figure 2 is a transverse, vertical section, as taken on line 2—2 of Figure 1, looking in the direction indicated by the arrows;

Figure 3 is an enlarged detail of the chain carried pick-up and associated mechanism at the front of the machine; and

Figure 4 is an enlarged elevational detail of the patter plate operating against the back of the card pack.

Housed in a suitable, box-like cabinet 4, with a large rectangular window opening 2 occupying the most of the lower half of the front wall 3 thereof is the compact, quiet-running and efficient card changing mechanism here shown as contained in a shell frame 4.

Mounted along opposite sides of the frame, at a level just above the top of the window opening 2 are horizontal side rails 5 from which a plurality of framed display cards 6 are suspended by hollow top rods 7. These cards 6, to the

2

number of twenty, thirty or forty, are hung one behind the other, being spaced by the diameter of their top suspending rods 7 that fill the rails 5 from front to back. The rails 5 each possess in addition to its rod-supporting surface, a vertically spaced offset flange 5^a that overlies the ends of the rods and terminates short of the rail proper at both front and rear ends a distance about equal to the diameter of one of the card frame-supporting rods 7. The size of the framed cards is preferably just larger than the window opening 2 through which the front card of the pack is exhibited to view.

A pair of endless chains 8 run around opposite sides of the frame 4 being supported by idlers 9 at front and back at the top and at the bottom front and being driven by spaced chain sprockets 10 at the bottom back, keyed on a transverse horizontal shaft 11 carried by the frame 4 and driven through a meshing worm and gear assembly 12 by the motor 13.

In corresponding position on both chains 8, a pick-up fitting 14 is inserted instead of a link and each is provided with an inwardly projecting, horizontal pin 15 that is designed to engage and nest in the end of the card-carrying hollow rod 7, the lower half of which is cut away at the end as seen in Figure 3. Here too, it will be observed that the side rails 5 and notched as at 5^b to pass the pick-up pins 15 where the chains 8 run up the front of the machine at opposite sides.

Rotating clockwise, as seen in Figure 2, these chains pick up the front card 6, lift it clear of the cabinet window 2, exposing the next succeeding card to view, then carry it rearwards over the rail-carried card pack and drop it down at the back of the horizontally assembled cards until the ends of the card rod 7 strike the rear ends of the rails 5 leaving it suspended there while the chains continue on their way.

To keep the card pack always moving forwards so that a newly exposed card at the front advances to the foremost position on the side rails formerly occupied by the last lifted card and similarly in proper position to be engaged in its turn by the pick-up fittings in the continually travelling chains, a patter plate 16 is located across the back behind the card pack.

It is formed as a broad and slightly flared V, turned on edge and centrally pivoted by its in-turned end flanges 16^a to the sides of the frame 4. Coil springs 17 stretched from each end to the side rails 5 draw in the upper end until stopped by engagement with the rail end. As

the last seen card 6 is dropped down the back of the machine to take its rearmost position in the pack, it passes in front of the wide flared mouth of the patter plate V but just as its rod is about to be deposited on the rails 5, a wedge shaped spreader extension 14^a on the pick up fittings engages the flared end of the upper arm of the patter plate V hinging it outwardly against the action of the spring 17 and causing the lower arm of the patter plate to hinge inwardly against the pack of suspended cards, pushing them all forwards. Similarly, when the wedge-like fitting has passed, the upper arm of the patter plate V is drawn in by the action of the spring to nose all the card-carrying rods forwards.

Continuously the carrier chain mechanism operates, successively picking up the front exposed cards at equal intervals and quietly and smoothly reinserting them in undisturbed rotation at the back of the pack.

From the foregoing description taken in connection with the accompanying drawings, it will be manifest that a card displaying apparatus is provided that will fulfill all the necessary requirements of such a device, but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention, what is claimed as new is:

1. In a card changing apparatus enclosed within a windowed, box-like cabinet, a pair of spaced horizontal side rails projecting inwardly from opposite sides, a plurality of independent cards each with a horizontal rod across the top suspended from said rails in a horizontal pack one behind the other with the front-most in registry with and viewable through the cabinet window, said cards being slidable on said side rails with the cross rods thereof substantially filling said rails from end to end, card moving mechanism engageable with the front-most card in the pack and operable over the pack to reinsert the engaged card at the rear comprising a spaced pair of endless chains with correspondingly placed card pick-up fittings included therein, said fitting each having an inwardly projecting horizontal pin, spaced idlers supporting and driving means for said chains, and a card moving mechanism-operated card pack patter acting on the rear of said card pack; said side rails each comprising a vertically spaced pair of inwardly projecting flanges with the upper flange being narrower and ending short of the lower flange at both ends by a distance substantially equal to the diameter of one of said card rods and the lower flanges on which the card rods are sup-

ported having notches on the outer sides at their ends to pass the inwardly projecting horizontal pins of said pick-up fittings.

2. In a card changing apparatus enclosed within a windowed, box-like cabinet, a pair of spaced horizontal side rails, a plurality of independent cards suspended therefrom in a horizontal pack one behind the other with the front-most in registry with and viewable through the cabinet window, said cards being slidable on said side rails and substantially filling the same from end to end, card-moving mechanism engageable with the front-most card in the pack and operable over the pack to reinsert the engaged card at the rear comprising a spaced pair of endless chains with correspondingly placed card pick-up fittings included therein, spaced idlers supporting and driving means for said chains, a card moving mechanism-operated card pack patter acting on the rear thereof, said patter comprising a pair of patter plates pivotally mounted in said cabinet each with a flared mouth on its upper side and normally held in engagement with the rear of one of said side rails by a retractile spring, and a wedge-shaped patter plate spreader carried by each of said chains.

3. The combination with the structure set forth in claim 1 wherein said card pack patter comprises a pair of pivotally mounted, flared-mouth patter plates normally spring held against the rear end of the respective side rails, and wedge-shaped spreader extensions on said pick-up fittings engageable with the flared mouths of said plates.

4. The combination with the structure set forth in claim 1 wherein said card pack patter comprises a pair of centrally pivoted patter plates each formed as broad slightly flared V's turned on edge, a coil spring stretched from each side rail to a respective patter plate normally holding the top of the plate against the rear end of the lower flange of the rail, and wedge shaped spreader extensions on said pick-up fitting engageable with said pivoted patter plates forcing the upper end thereof outwards against the action of said coil springs and simultaneously kicking the bottoms thereof in against the card pack.
